UNITED STATES PATENT OFFICE.

EDMUND F. KITTOE, OF CHICAGO, ILLINOIS.

VENTILATOR WHEEL OR FAN.

SPECIFICATION forming part of Letters Patent No. 329,052, dated October 27, 1885.

Application filed June 2, 1884. Serial No. 133,632. (No model.)

To all whom it may concern:

Be it known that I, EDMUND F. KITTOE, residing at Chicago, in the county of Cook and State of Illinois, and a citizen of the United States, have invented a new and useful Improvement in Ventilator Wheels or Fans, of which the following is a full description, reference being had to the accompanying drawings, in which—

10 Figure 1 is a front elevation of the wheel or fan when used as an exhaust; Fig. 2, a rear elevation of the same; Fig. 3, an outline showing the manner of forming and arranging the blades; Fig. 4, a rear elevation showing the back with the discharge-openings contracted; Fig. 5, a vertical section on a smaller scale.

This invention relates to that class of rotary fans for forming or exhausting air in which a current is produced in a direction at 20 right angles to that of the motion of the blades of the fan, the latter being mounted on a rotary shaft and arranged within a suitable casing or air-passage.

The invention consists in the special formation of the blades of the fan and their peculiar arrangement upon a rotary shaft, which will be hereinafter fully described, and then set forth in the claims.

In the drawings, A represents the hub or center; B, the fan or blade portion; C, the opening in which the wheel or fan is located; D, the shaft on which the hub A is mounted; E, boxes supporting the shaft D; F, a bar on which the boxes are secured; G, a brace or support for the bar F.

The hub A may be made of solid material, as shown, or it may be made of a band with end pieces, or in any other suitable manner, and its diameter will depend upon the diameter of the wheel—the larger the wheel the greater in diameter the hub—and this hub is to be keyed or otherwise suitably secured to a shaft, D, on which shaft is a pulley-wheel, D', by means of which and a belt, D'', or other driving device, the shaft can be revolved to 45 revolve the wheel or fan.

The acting portion of the wheel or fan B is formed of a series of wings or blades, a, the inner ends, a'', of which are bent around and 50 secured in any suitable manner to the hub A, and the bend of the wings or blades a is one

which projects their forward or receiving edges, so as to overhang the plane of the hub or center, as shown. The back of the acting portion is formed of a spider, so as to leave a series of openings extending from near the periphery of the hub to the periphery of the circumference of the back, to coincide with the openings between the blades or wings. The arms b of this spider for a small wheel 55 may be formed of the same piece of material as the wings or blades, as shown in Fig. 3, the material being cut out to leave openings, as shown in said Fig. 3, and the arms b of the spider being secured at their inner ends, b'', 60 in any suitable manner to the hub, while their outer ends, b', form a connection to the wings a, the wings being cut, as shown in Fig. 3, and being bent or curved around, as there 65 shown, to have their inner ends lap on and be secured to the hub. 70

The spider may be formed of an independent piece, as shown in Figs. 4 and 5, in which case the outer ends of the wings are turned down and riveted, or otherwise secured to the 75 rim or wings b' of the spider-arms, as shown in Fig. 5, the inner ends of the spider-arms being continuous with the center, to which the hub A may be bolted or otherwise secured.

When the spider is formed as shown in 80 Figs. 1 and 2, a greater area of opening is left than when the spider is formed as shown in Fig. 4, and if desired the wheel might be formed as shown in Fig. 2, and strips be secured to its rear face to contract the openings, 85 the object being to increase or decrease the amount of discharge to suit the capacity of the wheel or the degree of exhaust required.

The wings or blades being curved, as shown, it will be seen that their peripheries c at the 90 front edge project beyond the periphery formed by the rear face, thereby increasing the diameter of the wheel the difference between the circle of the projecting portion c and the circle of the rear, thus increasing largely the 95 capacity of the wheel.

The curvature of the wings or blades in the manner shown causes their bent edge to overlap the rear edge of the preceding wing or blade, forming a passage, d, between the respective wings, which passage decreases in 100 size as it extends rearward. The passages d

thus formed between the wings or blades extend the entire distance from the top to the bottom of the wing or blade, diminishing toward the rear, but leaving an unobstructed 5 passage, and one which will receive air for its entire length and discharge the air in the same manner, thus preventing any vacuum around the hub and insuring an increased capacity for discharge.

10 The curving of the wings or blades, as shown and described, forms buckets by which the wheel can be as readily used for a force-fan as well as an exhaust one, the shape of the buckets being one that will as readily receive 15 and discharge from the rear as from the front, owing to the divergence produced by the manner of bending, and to change the fan from an exhaust to a force all that is necessary to be done is to cross the belt, if a belt is used for 20 driving, or to reverse the driving-power, giving the fan a reverse rotation.

The rear edge of the opening in the back or spider coincides in curvature with the curvature of the blade or wing, and the rear edge 25 of the blade or wing is secured, by riveting, brazing, or in any other suitable manner, to the rear edge of the opening with which it coincides. The wings or blades, it will be seen, have a gradual rearwardly-inclined pitch,

30 with their lower ends running parallel and rearwardly to the plane of the circumference of the hub, and their upper end with a rearwardly and inward pitch, producing a wide mouth or opening for the receiving side, which 35 opening contracts gradually toward the delivery side, by which the air caught by the front side will be drawn in for the entire size of the opening, with a free discharge from the top to the bottom, and by giving the receiving- 40 edge a curved projection forward of the plane of the forward end of the hub or center, which projection increases gradually in width as it rises from the hub or center to a line in a plane with the forward end of the hub or center, it 45 will be seen that a greater receiving capacity is provided than if the forward edges of the

wing were on a straight diagonal line from the hub to the periphery of the wings.

The diameter for the back or rear face of the fan or wheel being smaller than the actual 50 diameter formed by the outer ends of the wings or blades enables the fan to be set in an opening the diameter of which corresponds to the diameter of the rear or back, thus enabling the fan to be placed in position, with 55 the outer ends of the wings or blades beyond the circumference of the opening, thereby increasing the capacity of the wheel or fan.

What I claim as new, and desire to secure by Letters Patent, is—

1. The ventilator fan or wheel composed of the hub A and the wings a, the outer edges of the wings connected with each other and describing the periphery of the rear face of the wheel in the plane of said face, and the wings 65 being curved, substantially as shown, from said point to the hub, with the longest curve on the receiving-face and the shortest on the rear face of the wheel, the inner ends of the blades being secured to the hub obliquely to the axis 70 thereof, whereby the wings will project beyond the periphery of the rear face of the wheel, and thereby increase the diameter of the wheel adjacent to such face, substantially as described.

2. The ventilating fan or wheel composed of the hub A and the wings a, the outer ends of the wings being connected with each other and describing the periphery of the rear face of the wheel in the plane of said face, and the 80 wings being curved from said point to the hub obliquely to the axis of the hub, and secured to the latter obliquely to its axis, the front edge of one wing overlapping the rear edge of the preceding wing to form a passage, d, from 85 the periphery of the wheel to its hub, decreasing in size from the front to the rear face of the wheel, substantially as described.

EDMUND F. KITTOE.
